UNWINDING MECHANISM FOR BRAIDING-MACHINES.

1,117,438.

Specification of Letters Patent.

Patented Nov. 17, 1914.

Application filed April 1, 1914. Serial No. 828,788.

To all whom it may concern:

Be it known that we, (1) HANS ALBERT PHILIPS and (2) GUSTAV PIEPENERING, (1) a citizen of the United States and (2) a subject of the Emperor of Germany, both residing at Bridgeport, county of Fairfield, State of Connecticut, have invented an Improvement in Unwinding Mechanism for Braiding-Machines, of which the following is a specification.

This invention has for its object to provide unwinding mechanism for braiding machines that will permit the use of very much longer and larger spools or bobbins than has heretofore been possible, thus effecting a great saving in the cost of manufacture of braided cord.

So far as we are aware, only relatively short spools have heretofore been used in braiding machines for the reason that the pull upon the thread caused breakage when drawing from either the upper or lower end of the spool if the length of the spool was increased.

Our present invention enables us to overcome this difficulty and to use long spools with greatly increased carrying capacity. This we accomplish by providing unwinding mechanism that will rotate the spools mechanically when the pull upon the threads increases beyond the normal, as when drawing from either the upper or lower ends of the spools.

With this object in view we have devised the novel mechanism which we will now describe, referring to the accompanying drawings forming a part of this specification and using reference characters to indicate the several parts.

Figure 1 is a plan view of a portion of a braiding machine showing a sufficient number of spool carriers to illustrate the principle of the invention; Fig. 2 an elevation on an enlarged scale of one of the sets of spring fingers; Fig. 3 an elevation of a spool carrier showing the driving wheel locked to prevent the unwinding of surplus thread; Fig. 3a a detail sectional view on the line 3a-3a in Fig. 3, looking in the direction of the arrows; Fig. 4 a similar view showing the position of the parts when thread is being drawn from either end of the spool; Fig. 5 a similar view illustrating

a variant form of lifting mechanism, the driving wheel being locked, as in Fig. 3, a spring finger being shown, but not in its correct position relatively to the carrier, and a spool, and thread being indicated by dotted lines. Fig. 6 a similar view partly in section, the parts being in position as when drawing thread from the central portion of the spool. Fig. 7 a similar view showing the parts in position as when drawing thread from either end of the spool; Fig. 8 a detail sectional view and Fig. 9 an inverted plan view of the spool detached; Fig. 10 a section on an enlarged scale on the line 10-10 in Fig. 5, looking in the direction of the arrows, and Fig. 11 is a detail elevation of the spindle, sleeve and driving wheel attached.

20 denotes the foot of the carrier, 21 a standard extending upward therefrom and 22 a spool spindle likewise extending upward from the foot. Below the foot the carrier is of any ordinary or preferred construction. It is sufficient for the purposes of this specification to state that the spool carriers are caused to travel along the serpentine grooves 23 in the bed plate 24 in a manner common to this type of braiding machines. For convenience in description we will indicate the carriers traveling in one direction by A and the carriers traveling in the opposite direction by B. Cooperating with carriers A are sets of spring controlled fingers 25 mounted upon bases 26 and cooperating with carriers B are sets of spring controlled fingers 27 mounted upon bases 28. Rotatably mounted on the spindle is a sleeve 29 which carries a notched disk 30.

31 denotes a driving wheel which is keyed to the sleeve but is adapted to be moved longitudinally thereon. The driving wheel 95 is provided on its face with a plurality of pins 32 which may be flattened upon one side as shown.

33 denotes the spool or bobbin which is provided in its under side with a recess 34 which receives disk 30 and with a pin 35 in said recess which is adapted to engage either of the notches in disk 30, so as to lock the spool against rotation independently of the disk and wheel.

36 denotes a tension weight which slides

freely on the standard. The thread 37 passes from the spool through an eye 38 at the mid-length of the standard, then downward under the tension weight and upward through an eye 39 at the top of the standard.

A vitally important feature of the invention is means for lifting the driving wheel into position to be engaged by the spring fingers.

40 denotes a lifting block which in the form illustrated in Figs. 3 and 4 is adapted to move vertically on a guide rod 41 extending upward from the foot of the carrier. A rod 42 extends upward from the lifting block and a coil spring 43 is connected to the upper end of the rod, the other end of the spring being connected to a slide 44 which is adapted to move freely on the standard. 20 The tension weight is so shaped as to balance on the standard and prevent the possibility of binding, rod 42 passing through an opening 45 without contact therewith.

46 denotes a lever, one end of which is pivoted to an arm 47 extending upward from the foot at the end opposite the standard, the other end of said lever being pivoted loosely to a lug 48 extending from the lifting block. The lever is widened at its mid-length and provided with a central opening which freely receives the hub 49 of the driving wheel and in the present instance is provided with bosses 50 (one only being shown) adapted to engage the under side of the driving wheel. The lifting block is provided with a detent 51, the face of which is adapted to engage the flattened faces of the pins 32 on the driving wheel to lock the driving wheel and with it the spindle and spool against rotation by momentum in case of a sudden pull upon the thread. This detent is preferably beveled down to an edge on its reverse face to reduce contact surface with the tops of the pins and insure its quick engagement with a pin.

The lifting mechanism in the form illustrated in Figs. 5, 6, 7 and 10 differs in that the lever and arm 47 are dispensed with and lifting block 40 is provided with a branched arm 52 which partly incloses the hub on the driving wheel and engages the under side of said wheel. The lifting block in this form travels on a guide 53 which is formed integral with the foot and standard. The downward movement of the driving wheel is limited in both forms by a flange 54 formed upon the foot, and its upward movement is limited by engagement with disk 30.

Spring fingers 25 and 27 are pivoted to their respective bases, as at 55. Springs 56 retain the fingers in their normal position and yield when they are engaged by the pins upon the driving wheel. Pins 57 serve as stops to limit the movement of the fingers when returned to their normal position. In

the case of fingers 27, the stop pins have the additional function of carrying the springs. In the case of fingers 25, the springs are carried by pins 58.

The operation is as follows: When thread is being drawn from the central portion of the spool or bobbin, the pull of the thread will raise the tension weight, which in turn will engage slide 44, and raise lifting block 40 to the position shown in Fig. 6, in which it will be noted that detent 51 has been raised above the top of the pins 32 upon the driving wheel, so as to leave said wheel unlocked, but said wheel has not been raised high enough to cause the pins thereon to engage the corresponding spring fingers 25 or 27 as may be. When the parts are in this position, the pull upon the thread will cause the spool, sleeve and driving wheel to rotate freely on the spindle. Any sudden pull upon the thread will be overcome and rendered harmless by the yielding of spring 43. Should the thread slacken, the tension weight will instantly drop away from slide 44 and will permit said slide, rod 42 and the lifting block to drop, which will permit the detent to drop between the pins 32 on the driving wheel, as in Figs. 3 and 5, and stop the rotation of the driving wheel and with it the sleeve and spool, and prevent the unwinding of surplus thread from the spool. Suppose now that thread is being drawn from the spool either above or below the central portion thereof. It follows that the pull upon the thread will be increased. As the pull upon the thread increases, the tension weight will be lifted above the position shown in Fig. 6 and will consequently raise slide 44 and the lifting block, the effect of which is to raise the driving wheel by means of a lever 46 or branched arm 52, as may be, to the position shown in Figs. 4 and 7, in which position it will be noted that the driving wheel has been raised high enough to carry its plane of rotation into the plane of the spring fingers, so that as the carriers travel along the serpentine grooves, the pins 32 upon the driving wheels of the carriers specifically indicated by A will be caused to engage spring fingers 25 and the pins 32 upon the driving wheels of the carriers specifically indicated by B will be caused to engage spring fingers 27. The force of the blows of the pins upon the fingers is taken up by the yielding of springs 56, but the effect of the engagement of successive pins with successive fingers is to impart rotation to the driving wheel, sleeve and spool so that thread will be delivered therefrom as fast as required, but without any pull upon the thread, so that all danger of breakage of the thread, even when very long and large spools are used, is eliminated. The instant thread is drawn from the central portion of the spool again and

the pull upon the thread drops down to normal, the tension weight, slide 44, the lifting block and the driving wheel, will drop down to substantially the position shown in Fig. 6, which will place the pins upon the driving wheel below the plane of the spring fingers, and out of engagement therewith, and the spool, sleeve and driving wheel will be free to be rotated by the pull of the thread until either an increase of pull upon the thread again raises the tension weight, slide, lifting block and driving wheel into position to again cause the driving wheel, sleeve and spool to be rotated by the fingers, or until slack of the thread permits the tension weight, slide and lifting block to drop down, as in Figs. 3 and 5, and the detent to stop rotation of the driving wheel, sleeve and spool. It should be understood that this locking of the driving wheel would be of very brief duration in use, as the normal pull upon the thread will quickly raise the weight, slide and lifting block and release the driving wheel, as in Fig. 6, which would again leave said wheel, the sleeve and the spool free to be rotated by the pull of the thread.

Having thus described our invention we claim:

1. A spool carrier comprising a spindle, a standard, a spool-carrying sleeve on the spindle, a driving wheel keyed to the sleeve and longitudinally movable thereon, means engaging the driving wheel for rotating said sleeve, a slide on the standard, a lifting block connected to the slide and provided with a detent, means operated by the lifting block for raising the driving wheel and a tension weight raised and lowered by the pull of the thread and adapted to engage the slide, whereby when the pull upon the thread is normal, the driving wheel will be released, when the pull lessens the weight and lifting block will drop and when the pull upon the thread increases above the normal the driving wheel will mechanically rotate the spool.

2. In a braiding machine, the combination with a spool-carrying sleeve and a driving wheel keyed thereto and longitudinally movable thereon, of a lifting block having a detent adapted to lock the driving wheel, means for raising the lifting block to disengage the detent and the driving wheel, means operated by the lifting block for raising the driving wheel and means acting to rotate the driving wheel and sleeve when said wheel is raised into position for engagement.

3. In a braiding machine, the combination with a spool-carrying sleeve and a driving wheel keyed thereto and longitudinally movable thereon, of means for driving said wheel when in engaging position, a tension weight and means intermediate said weight

and the driving wheel for raising said wheel into engaging position when the pull upon the thread is increased above the normal.

4. In a braiding machine, the combination with a spool-carrying sleeve and a driving wheel keyed thereto and longitudinally movable thereon, of means for driving said wheel when in engaging position, a lifting block having means for raising said wheel, a tension weight and connections intermediate said weight and the lifting block, whereby said block is raised and raises the driving wheel into engaging position when the pull upon the thread is increased above the normal. 70

5. In a braiding machine, the combination with a spool-carrying sleeve and a driving wheel keyed thereto and longitudinally movable thereon, of means for driving said wheel when in engaging position, a lifting block having means for raising said wheel, a detent on said block adapted to lock the driving wheel, a tension weight and connections intermediate said weight and the lifting block, whereby the driving wheel is released when the pull upon the thread is normal, is locked when the pull slackens and is raised into engaging position when the pull is increased above the normal. 80

6. In a braiding machine, the combination with a spool-carrying sleeve and a driving wheel keyed thereto and longitudinally movable thereon, of means for driving said wheel when in engaging position, a lifting block having means for raising said wheel, a tension weight, a slide adapted to be engaged by said weight, for the purpose set forth, and a yielding connection between the slide and the lifting block. 95

7. In a braiding machine, the combination with a spool-carrying sleeve, a driving wheel having pins on its face and keyed to the sleeve and longitudinally movable thereon, a tension weight and means intermediate said weight and the driving wheel 100 for raising said wheel, of spring controlled fingers adapted to be engaged by the pins on the driving wheel and impart rotation thereto when said wheel is raised into engaging position. 105

8. In a braiding machine, the combination with a spool-carrying sleeve, a driving wheel longitudinally movable thereon, a tension weight and means intermediate said weight and the driving wheel for raising 110 said wheel, of fingers adapted to be engaged by the driving wheel whereby rotation is imparted to said wheel when it is raised to the engaging position. 115

9. In a braiding machine, the combination with a spool-carrying sleeve, a driving wheel longitudinally movable thereon, and means for imparting rotation to said wheel when raised into engaging position, of a lifting block, means operated thereby for raising 120

the driving wheel, a rod extending from said block, a slide, a spring intermediate said rod and slide and a tension weight by which the movements of the slide and lifting block are controlled.

10. In a braiding machine, the combination with a spool-carrying sleeve, a driving wheel longitudinally movable thereon, and means for imparting rotation to said wheel when raised into engaging position, of a lifting block having a detent adapted to lock the driving wheel, means operated by said block for raising the driving wheel, a slide, a yielding connection between said slide and block and a tension weight adapted to engage the slide and cause the detent to release the driving wheel and to raise said wheel into engaging position, substantially as described.
20. 11. In a braiding machine, the combination with a spool carrier having a foot provided with an arm and a standard, a spool-carrying sleeve, a driving wheel longitudinally movable thereon and means for imparting rotation to said wheel when raised into engaging position, of a lifting block having a lug, a lever pivoted to said lug and to said arm and adapted to raise the driving wheel, a slide on the standard, a yielding connection between said slide and the lifting block and a sliding tension weight on the standard adapted to engage the slide.
30. 12. In a braiding machine, the combination with a spool carrier having a foot provided with an arm and a standard, a spool-carrying sleeve, a driving wheel longitudinally movable thereon and means for imparting rotation to said wheel when raised into engaging position, of a lifting block having a lug, and a detent adapted to lock the driving wheel, a lever pivoted to said lug and to said arm and adapted to engage the driving wheel, a slide on the standard, a yielding connection between said slide and the lifting block and a sliding tension weight on the standard adapted to engage the slide.
40. 13. In a braiding machine, the combination with a spool-carrying sleeve, a driving wheel having pins on its face and longitudinally movable on the sleeve and means for imparting rotation to said wheel when raised into engaging position, of a lifting block having a detent adapted to lock the driving wheel, means operated by said block for raising the driving wheel, a slide, a yielding connection intermediate said slide and the lifting block, and a sliding tension weight adapted to engage the slide.

50. 14. In a braiding machine, the combination with a spool-carrying sleeve, a driving wheel having pins on its face and longitudinally movable on the sleeve and means for imparting rotation to said wheel when raised into engaging position, of a lifting block having a detent adapted to lock the driving wheel, means operated by said block for raising the driving wheel, a slide, a yielding connection intermediate said slide and the lifting block, and a sliding tension weight adapted to engage the slide.

60. 15. In a braiding machine, the combination with a spool carrier having a foot provided with an arm and a standard, a spool-carrying sleeve, a driving wheel longitudinally movable thereon and having pins on its face and means for imparting rotation to said wheel when raised to engaging position, of a lifting block having a lug and a detent adapted to engage the pins on the driving wheel, a lever pivoted to said lug and to said arm and adapted to raise the driving wheel, a slide on the standard, a yielding connection between said slide and the lifting block and a sliding tension weight on the standard adapted to engage the slide.

70. 16. In a braiding machine, the combination with a spool carrier having a foot provided with an arm and a standard, a spool-carrying sleeve, a driving wheel longitudinally movable thereon and having pins on its face, and spring controlled fingers adapted to engage said pins, for the purpose set forth, of a lifting block having a detent adapted to engage the pins to lock the driving wheel, means operated by the lifting block for raising the driving wheel, a slide on the standard with which the lifting block is connected and a sliding tension weight on the standard adapted to engage the slide.

In testimony whereof we affix our signatures in presence of two witnesses.
